UNITED STATES PATENT OFFICE.

EARL B. SCOTT, OF EAST ORANGE, NEW JERSEY, ASSIGNOR TO E. I. DU PONT DE NEMOURS & COMPANY, OF WILMINGTON, DELAWARE, A CORPORATION OF DELAWARE.

METHOD OF DRYING AND TRAY FOR USE IN THE PERFORMANCE THEREOF.

1,409,473.

Specification of Letters Patent. Patented Mar. 14, 1922.

Application filed December 24, 1919. Serial No. 347,208.

To all whom it may concern:

Be it known that I, EARL B. SCOTT, a citizen of the United States, and a resident of East Orange, in the county of Essex and 5 State of New Jersey, have invented a certain new and useful Method of Drying and Tray for Use in the Performance Thereof, of which the following is a specification.

This invention relates to a method of 10 drying articles such as bristles, and to a tray for use in the carrying out of the method. Bristles and characteristically similar articles have a tendency to not dry straight, for example hog bristles have a tendency to 15 resume their natural curve, and also are liable to deterioration of color and texture when subjected to long continued heating. By the present method bristles can be dried straight and without deterioration in color 20 and texture, the method comprising the steps of combing the bristles straight and holding them straight during the drying; and separating the bundle of bristles to be dried into a large number of small separated 25 groups or tufts, whereby the drying medium can effectively and quickly reach all the individual bristles, thereby reducing the drying time to a minimum. By the use of a tray embodying the invention, as it relates to 30 apparatus, the method can be carried out conveniently and satisfactorily.

One object of the invention is to provide a method whereby bristles, and characteristically similar articles, can be dried 35 straight and without deterioration.

Another object is to provide a tray by the use of which the above indicated method can be conveniently carried out.

To these ends, and also to improve generally upon methods and devices of the character indicated, my invention consists in the matters hereinafter described and claimed.

In the accompanying drawings:—

Figure 1 is a plan view of a tray embodying the invention, as it relates to apparatus, the combs being omitted;

Figure 2 is a cross-sectional view of the tray illustrated in Figure 1, taken substantially on the line 2—2 of Figure 1, and 50 showing a comb in place in substantially the position it would occupy were bristles present, but with the bristles omitted to avoid confusion.

Figure 3 is a fragmental sectional view

taken substantially on the line 3—3 of Figure 2;

Figure 4 is a plan view of the tray illustrated in Figure 1, filled with bristles and with the combs in place;

Figure 5 is a plan view of a tray having 60 the inventive characteristics of the tray illustrated in Figures 1 to 4, but consisting of a plurality of bays, detailed illustration of the bottom of the tray proper, and also illustration of the combs for all but one 65 bay, being omitted for simplicity;

Figure 6 is a plan view of a somewhat modified tray, the combs being omitted, and

Figure 7 is a cross-sectional view of the tray illustrated in Figure 6, substantially 70 on the line 7—7 of Figure 6, and showing a comb fixed in final position.

To avoid lack of clearness in the figures the spacing and size of the teeth of the combs, and of the apertures in the bottom, 75 are exaggerated with respect to the size of the frame.

I shall first describe the tray, and, then, the method as carried out with the aid of the tray.

Referring now to the drawings, and more particularly to Figures 1 to 4 inclusive:—

The illustrated tray comprises a tray proper, receptacle, or container, 1, and a series of three positioning-separators, or 85 combs, 2. The bottom 3 of the receptacle is provided with apertures (Figure 1) including a series of spaced rows 4, of tooth-receiving apertures 5, the apertures of different rows being in alignment. Each comb 90 2 has its teeth 6 spaced in correspondence with the spacing of rows 4, the rows 4 being equally spaced in the present instance, and the teeth being correspondingly equally spaced. The combs are each of a length 95 permitting them to be received between the sides 1^a of the receptacle frame and have their teeth of a size to fit in the apertures 5 with a small side-to-side clearance and with a somewhat greater front-to-back clear- 100 ance, the series of teeth being, of course, so located on the backs 7 of the combs that when the backs are received between the sides 1^a the teeth shall register with the apertures 5. Desirably the height of each 105 comb is somewhat greater than the over-all height of the receptacle 1, and the teeth are of less height than the frame.

In carrying out the method with the aid of the tray the procedure is preferably as follows (see Figure 4):—A suitable quantity of bristles B is placed in the receptacle 5 or tray proper, then the central comb is applied to the bristles, its teeth positioning them and initiating the separation of them into a large number of small groups or tufts, and the teeth are inserted in the proper row 10 of apertures 5 across the receptacle to fix the comb. Next, the second comb is inserted in the bristles at the side of the central comb, with its teeth in alignment with the teeth of the central comb and conforming to the 15 grouping initiated by the central comb; then it is pulled to the extreme butt ends of the bristles, this action combing the bristles straight and carrying forward the separation initiated by the central comb, and its 20 teeth are then inserted in certain of the apertures 5 whereby the comb is fixed in position to hold the bristles. (In moving the comb it may, conveniently, be somewhat inclined from the vertical and in the direction 25 of travel, to facilitate its passing the apertures in the bottom). Lastly, the third comb is inserted in the bristles on the opposite side of the central comb, in accordance with the grouping initiated by the central comb, 30 is drawn toward the flag ends of the bristles, and is fixed, thereby combing, grouping, straightening and holding the bristles. The tray is now placed in any suitable drying means and the drying carried out in any desired manner, preferably by blowing drying air at regulated temperature through the tray. It will be understood that the order 35 of introducing and manipulating the combs can, of course, be varied if desired; also, the 40 combing step may be performed more than once with a comb, before fixing the comb, if for any reason it be desired.

With the above procedure the bristles are separated into a large number of small groups 45 or tufts—in practice the teeth of a comb are desirably but about $\frac{1}{16}$ inch apart—which groups are quickly and thoroughly penetrated by the drying air, so that the bristles can be dried very quickly, the drying taking 50 in some cases less than an hour, instead of the three or four days of the old practice; and previous difficulties, such as deterioration in color and texture due to prolonged heating, are eliminated. Also, the bristles 55 are combed out straight and held straight, the combing action straightening out the bristles in a highly satisfactory way and the combs being a simple and satisfactory means for holding the bristles straight.

60 The frame of the receiver may desirably be of wood, and the bottom may be of perforated brass attached to the frame in any suitable manner, as by wood screws 8. While three combs have been referred to it will be 65 understood that any suitable number desir-

able for carrying out the objects of the invention may be used.

If desired, a tray embodying the invention may be made to include a series of bays each of suitable size to receive the bristles to 70 be treated and each furnished with combs, such a tray being, in effect, a number of structurally joined trays similar to the single tray described above. A tray of this type is illustrated somewhat conventionally 75 in Figure 5, where the tray 9 is shown as having eight bays. In practice each bay is furnished with three combs, as 10, similar to the combs 2 and similarly fitting into the apertures of the bottom. Various other 80 modifications may be adopted. For example, in the structure illustrated in Figures 6 and 7, the bottom 11 of the tray proper 12 is made up of a number of wires 13 attached to the frame 14 in any suitable manner, and 85 suitably spaced to provide apertures 11^a in the bottom, the apertures being somewhat larger than those in the bottom 3 of the receptacle 1, and being adapted to receive a plurality of teeth 15 of the combs, as 16. 90 Each end of the frame includes a supplemental shelf-like member 17, each member being slotted at 18 at points corresponding to the desired positions of the combs 16. Each member 17 is slightly higher than the 95 distance from the points of the teeth 15 to the undersides of the overhung portions 19 so that, with the portions 19 resting upon the members 17, the combs may be moved along with their teeth clearing the bottom 100 11. When the combs have been brought opposite the slots they are dropped therein and fixed, the teeth of the combs resting in the apertures 11^a.

As previously mentioned, in the drawings 105 the spacing and size of the teeth and of the apertures in the bottom are exaggerated with respect to the size of the frame, in order to avoid lack of clearness. In practice, one of the bays (Fig. 5) or a single-bay receptacle (Figs. 1 and 6) may conveniently 110 be about 7x11 $\frac{1}{2}$ inches inside dimensions, and a comb may be about 11 $\frac{3}{8}$ inches in length and have 30 teeth.

Also, as previously mentioned, the introducing and manipulation of the combs may 115 be varied. For example the initial separation may be accomplished with one of the end combs instead of with the central comb, the bristles may be initially combed somewhat before fixing them, and so on.

Although I have described the invention with more particular reference to the illustrated apparatus, and have described a preferred way of practicing the method, I do 125 not restrict the invention to such apparatus or to the method as preferably practiced.

Having thus described my invention what I claim is:—

1. In a drying tray for bristles and simi- 130

- lar articles, a receptacle element for directly and immediately receiving the articles, and an element insertable in said directly receiving receptacle element for 5 forming the separation of said articles as they lie in the receptacle element to thereby separate said articles into groups, said insertable element having a device located for insertion between said articles to accomplish 10 said separation.
2. In a drying tray for bristles and similar articles, a receptacle element for directly and immediately receiving the articles, and an element receivable in and movable in said directly receiving receptacle element and having a device located for insertion between said articles as they lie in the receptacle element to thereby separate said articles into groups.
- 15 3. In a drying tray for bristles and similar articles, a receptacle element for directly and immediately receiving the articles, and an element receivable in and movable in said directly receiving receptacle element and having a device located for insertion between said articles as they lie in the receptacle element to thereby separate said articles into groups, there being provisions for the fixing of said elements with respect 20 to each other.
- 30 4. In a drying tray for bristles and similar articles, a receptacle for directly and immediately receiving the articles, and a comb insertable in said receptacle and having a tooth located for performing the separation of said articles into groups as they lie in said receptacle.
- 35 5. In a drying tray for bristles and similar articles, a receptacle for the articles and comprising a frame having a bottom provided with a plurality of apertures, and a positioning-separator insertable in said frame and having an element located for separating the articles into groups as they 40 lie within said frame and upon said bottom, and for fixing them as separated.
- 45 6. In a drying tray for bristles and similar articles, a receptacle for the articles and comprising a frame having a bottom provided with a plurality of apertures, and a plurality of cooperating positioning-separators insertable in said frame and each having an element located for separating the articles into groups as they lie within said 50 frame and upon said bottom, and for fixing them as separated.
- 55 7. In a drying tray for bristles and similar articles, a receptacle for the articles, and a comb receivable in said receptacle for separating said articles into groups as they lie in said receptacle, said comb being movable in said receptacle thereby to provide for the 60 combing of said articles.
- 65 8. In a drying tray for bristles and similar articles, a receptacle element for the articles and a comb element receivable in said receptacle element for separating said articles into groups as they lie in said receptacle element, said comb element being movable in said receptacle element thereby 70 to provide for the combing of said articles, there being provisions for the fixing of said elements with respect to each other.
9. In a drying tray for bristles and similar articles, an open frame having a bottom provided with a plurality of apertures, and a comb movable in said frame, the teeth of said comb and the apertures of said bottom being relatively located and dimensioned to provide for the insertion of said 75 teeth into certain of said apertures.
10. In a drying tray for bristles and similar articles, an open frame having a bottom provided with a plurality of apertures, and a plurality of combs movable in said frame with respect to said frame and to each other, the teeth of said combs and the apertures of said bottom being relatively located and dimensioned to provide for the insertion of said teeth into certain of said 80 apertures.
11. In a tray for drying bristles and similar articles, a receptacle for the articles comprising an open frame having a bottom provided with a plurality of apertures, and a comb provided with a tooth-row of a length permitting the insertion of said row within the confines of said frame thereby to provide for the insertion of said teeth between the articles upon said bottom to 85 divide them into groups, said bottom being free from upstanding obstructions normally preventing free movement of said comb to and fro in said frame, thereby to permit 90 combing movement of said comb.
12. In a tray for drying bristles and similar articles, a receptacle for the articles comprising an open frame having a bottom provided with a plurality of apertures, and a comb provided with a tooth-row of a 105 length permitting the insertion of said row within the confines of said frame thereby to provide for the insertion of said teeth between the articles upon said bottom to divide them into groups, said bottom being free from upstanding obstructions normally preventing free movement of said comb to and fro in said frame, thereby to permit 110 combing movement of said comb, and there being means for optionally fixing said comb in 115 position in said receptacle.
13. The method of drying bristles and similar articles which comprises placing the articles upon a suitable support, combing said articles to separate them into a number of small tufts and to straighten them, fixing the position of the so separated and straightened articles upon said support, and 120

subjecting the articles to the action of a drying medium while they are so separated and held upon said support.

14. The method of drying bristles and 5 similar articles which comprises placing the articles upon a suitable support, beginning the separation of said articles into a number of small groups, fixing the position of the articles on said support, combing the

articles to carry forward the separation into 10 groups and to straighten the articles, fixing the position of the straightened articles upon said support, and subjecting the articles to the action of a drying medium while they are so positioned, grouped and held straight 15 upon said support.

In testimony, whereof I affix my signature.
EARL B. SCOTT.
